DESIGN FOR A COMBINED PERFUME HOLDER AND COVER

Florence N. Lewis, New York, N. Y.

Application May 18, 1939, Serial No. 85,063

Term of patent 7 years

To all whom it may concern:

Be it known that I, Florence N. Lewis, a citizen of the United States, residing at New York, in the county of New York and State of New York, have invented a new, original, and ornamental Design for a Combined Perfume Holder and Cover, of which the following is a specification, reference being had to the accompanying drawing, forming part thereof.

In the drawing:

Fig. 1 is a front elevational view of a combined perfume holder and cover showing my new design;

Fig. 2 is a side elevational view thereof.

Fig. 3 is a bottom plan view.

Fig. 4 is a front elevational view of the interior of the body portion.

Fig. 5 is a front elevational view of the interior of the cover.

I claim:

The ornamental design for a combined perfume holder and cover, as shown.

FLORENCE N. LEWIS.
